UNITED STATES PATENT OFFICE.

NILS MADSEN, OF WESTVILLE, NEW JERSEY.

SKEIN OR THREAD HOLDER.

1,076,898.

Specification of Letters Patent.

Patented Oct. 28, 1913.

Application filed January 10, 1913. Serial No. 741,158.

To all whom it may concern:

Be it known that I, NILS MADSEN, a subject of the King of Norway, and a resident of Westville, in the county of Gloucester and State of New Jersey, have invented certain new and useful Improvements in Skein or Thread Holders, of which the following is a specification.

My invention relates to improvements in devices for holding skeins or threads of embroidery silks and like material, and the object of my invention is to furnish a holder for this purpose in which skeins or single threads may be quickly put in place, which will prevent any snarling or tangling of the threads or skeins, which will so carry them that any color or shade of thread may be instantly located, and from which a thread may be quickly withdrawn without danger of displacing any of the other threads.

Beneath my thread holders is a platform or partition which forms the top of a box and between this top and the bottom of the box, there is a pocket which may be used to carry loose skeins of silk. When not in use the holder is closed by a cover which rests upon the base and protects its contents from light and dust.

In the accompanying drawings forming part of this specification and in which similar letters of reference indicate similar parts throughout the several views: Figure 1, is a top view of my holder, the cover being removed: Fig. 2, a section of Fig. 1 on line A—A, the cover being shown in place: Fig. 3, a section of Fig. 1 on line B—B, the cover being shown in place: Fig. 4, a plan of the front end of the holder showing the arrangement of the spring retainers at this end of the device.

1 is a base to which is fastened a plate 2 which carries the spring 3 and the part 4 which form a holder between which the ends of the thread or skein are secured. The part 4 is preferably constructed of a single piece of metal bent as shown best in Fig. 2 so that it has the general form of a toothed rack. The bights of the spring 3 are secured to plate 2 in any suitable manner, by a pin or screw 5 for instance, their outer, or forward, parts being so disposed as to lie close and parallel to the vertical parts and tops of the part 4 and their ends being bent upward as shown in Fig. 2.

6 is a platform, slotted at the forward end 55 at 7 for the passage of the parts 4 of the holder and carrying at its rear end hooks 8 and near its forward end hooks 9.

10 are foundation plates carried by platform 6 to assist in carrying hooks 8 and 9 60 and if the platform be made of pasteboard or some other light material some such strengthening pieces would be more essential than if it be made of wood or metal. If the hooks be fastened to the foundation plates 65 the platform would be furnished with slots 12 Fig. 3 so that the hooks can be passed through them conveniently prior to gluing or otherwise securing the foundation plates to the platform.

70 13 is a space or pocket between the base 1 and the platform 6 which can be used for carrying loose skeins or other articles.

14 is a cover, when in place resting upon the projecting sides and ends of base 1, for 75 inclosing the skein holder when not in use.

In placing a skein or thread its bight, or middle, is placed over one of the hooks 9 and its ends are carried backward one to and around one hook 8 the other to and around the next adjacent hook 8, and from these hooks forward to that top part 11 of the part 4 which corresponds to that hook 9 around which the bight of the skein or 80 thread is passed. The ends of the skein or 85 thread are held between the fingers of one hand and the skein is moved down until it rests upon the top 11 of the part 4 when a sidewise movement passes it in between the top 11 of part 4 and the upper horizontal 90 part of spring 3 and a downward movement brings it in between the vertical parts of the part 4 and the spring which is its final position in the holder. It will be observed that no manipulation of the device, other 95 than that caused by the movement of the skein or thread, is necessary in order to place the latter in or remove it from the clamp. To remove a thread it is only necessary to pull upon one of its ends until it is 100 completely withdrawn from the holder.

The threads are so disposed in the holder that all colors are in view at a glance and the arrangement of the threads upon the pins 8—9 permits a very long thread to be 105 carried in a holder of comparatively short length.

Having thus described my invention I

claim as new and desire to secure by Letters Patent:—

1. In a means for holding skeins or threads of silk or other material, in combination, hooks for carrying the main body of the skein or thread, and a holder for the opposite ends of the skein or thread, said holder consisting of a central rigid part upon opposite sides of which the said opposite ends are placed, and springs for holding said ends against the sides of said central rigid part.
2. In a means for holding the ends of a skein, in combination, a rigid member consisting of a horizontal top part and a vertical side part and a spring member lying close and parallel to said rigid member, the upper end of said spring member being bent so as to facilitate the entrance of the skein between it and the rigid member.
3. In a means for holding skeins or threads, in combination, a base, a platform above and carried by said base, a holder for the opposite ends of the skein or threads comprising a central part for engaging upon its opposite sides the opposite ends of said skein or threads and springs for holding said ends in contact with said sides, a hook near the front of said platform for holding the bights of said skeins or threads, and two hooks near the rear end of said platform around which opposite sides of said

skein or threads are passed before being carried to the spring operated holder at the front end of the device.

35

4. In a means for holding skeins or threads, in combination, a base, spring operated holders for the opposite ends of the skeins or threads carried by said base, a platform carried by said base, slotted for the passage of said spring operated holders, three hooks, one near the front and two near the rear of said platform, for carrying the body of said skein or threads, and a detachable cover carried by said base for covering said platform and the parts carried thereby.

40

5. In a means for holding skeins or threads, in combination, a base, a spring actuated holder carried by said base for holding the ends of the skein or thread, a platform above and forming with said base a pocket for loose skeins or threads, hooks carried by said platform for carrying the body of the skein or threads the ends of which are held by said spring actuated holder, and a detachable cover adapted to rest upon said base and in connection therewith to completely inclose the holder.
